(57) **CLAIM**

The ornamental design for a syringe, as shown and described.

DESCRIPTION

FIG. 1 is a top end perspective view of a syringe showing my new design.

FIG. 2 is a bottom end perspective view thereof.

FIG. 3 is a right side elevational view thereof.

FIG. 4 is a rear side elevational view thereof.

FIG. 5 is a left side elevational view thereof.

FIG. 6 is a front side elevational view thereof.

FIG. 7 is a bottom end plan view thereof; and,

FIG. 8 is a top end plan view thereof.

The broken lines are for illustrative purposes only and form no part of the claimed design.

The stippling in FIGS. 1-8 indicates a contrasting color (e.g., black, gray or another color), color intensity, texture and/or finish of the stippled portion of the design relative to the non-stippled portion of the design.
